UNITED STATES PATENT OFFICE

115,652

DESIGN FOR A JAR

Jack L. Hendrickson, Wheeling, W. Va., assignor
to Hazel-Atlas Glass Company, Wheeling,
W. Va., a corporation of West Virginia

Application November 25, 1938, Serial No. 81,363

Term of patent 14 years

To whom it may concern:

Be it known that I, Jack L. Hendrickson, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a front view of the jar showing my new design.

Figure 2 is a rear view thereof; and
Figure 3 is a perspective view thereof.

I claim:

The ornamental design for a jar, as shown.

JACK L. HENDRICKSON.
